Inventor,
Sam R. Smith
by J. M. Smith
Attorney.

UNITED STATES PATENT OFFICE.

SAM R. SMITH, OF LOS ANGELES, CALIFORNIA.

TENT STRUCTURE.

Application filed May 10, 1924. Serial No. 712,293.

To all whom it may concern:

Be it known that I, SAM R. SMITH, a citizen of the United States, and a resident of Los Angeles, in the county of Los Angeles and State of California, have invented new and useful Improvements in Tent Structures, of which the following is a specification.

This invention relates to and has for its main object the provision of an improved form of tent structure of composite character, and adapted to ride a collapsible frame, which, when its parts are fitted together will provide a rigid support for a tent capable of being readily assembled and dis-assembled at will.

In the consideration of this invention reference is had to my pending application for patent for tents, filed Dec. 18, 1922; Serial Number 607,698, the present invention disclosing numerous improved details and features of construction.

Another object is to provide in a tent structure a collapsible frame for supporting a tent, and a plurality of wind braces adapted to be adjusted to different positions and constituting guys for bracing the tent against the action of the elements, and arranged so that additional rigidity may be provided in the tent structure under extreme conditions.

Another object is to provide a frame composed of a sectional circular support composed of a plurality of normally straight sections formed of spring material such as spring steel or the like, and capable of being bent into arcuate form and held for supporting the hip of the tent, together with means for supporting said member on the tent.

Another object is to provide a tent structure including a tent having a single central supporting pole of sectional character, and a sectional member of circular form adapted to be supported on the tent in concentric relation to said pole, and means whereby when the lower edge of the tent is staked or otherwise attached to the ground and suitably guyed from the hip the rigid structure will be provided.

Still other objects will appear as the description progresses.

I have shown one preferred form of my invention in the accompanying drawings, in which:

Fig. 1 is a plan view of an assembled structure embodying my improvements.

Fig. 2 is a side elevation of the same.

Fig. 3 is an enlarged fragmentary section of the tent, showing means for adjustably supporting the tent frame.

Fig. 4 is a fragmentary interior view of the same.

Fig. 5 is a fragmentary section at the apex of the tent, showing the manner of attaching the tent to the supporting pole.

Fig. 6 is a fragmentary section at the lower edge of the tent, showing the manner of attaching the tent to the ground.

Fig. 7 is a side elevation of an umbrella tent embodying my improvements, with the skirt of the tent omitted.

Fig. 8 is a sectional plan of the structure shown in Figs. 1, 2 and 7 on line 8—8 of Fig. 2.

Fig. 9 is a fragmentary view of the tent, showing an improved type of guy or wind brace in position for bracing the tent under normal conditions.

Fig. 10 is a slightly reduced view of the same, showing the guy or wind brace arranged for supporting the tent under extreme conditions.

Fig. 11 is a fragmentary section similar to and showing the substitute for the frame supporting device shown in Fig. 3, and particularly adaptable to the form of tent shown in Fig. 7.

Fig. 12 is an enlarged view of a pair of sections forming the main circular tent supporting member, showing their normal and operative positions.

It will be understood in the consideration of this invention that in the construction of tents for use on camping expeditions and other purposes, it is desirable to provide a form of tent which can be quickly assembled and dis-assembled by unskilled persons, and to this end I have disclosed in the drawings and will describe in detail in this specification, my present improvements which embody but two primary supporting members for the tent, namely, a central pole and a circular frame concentrically arranged around said pole, over which the tent is adapted to be placed, and by means of which it is adapted to be held securely in position.

For convenience sake, the said supporting members are composed of short sections so that the entire structure, including the tent proper, may be rolled into a bundle of compact and convenient size, and altogether will provide a structure of minimum weight.

Now, referring particularly to the draw-

- ings, the tent T is composed of a conical upper section or top *t* formed of plurality of triangularly cut strips of material stitched together at their mating edges, and a lower skirt or wall portion *t'* also composed of a plurality of strips of material, preferably, though not necessarily, of uniform width throughout their length and similarly stitched together at their mating edges.
- 12 The tent T may also have a scalloped apron as at *a*, either forming an extension from the top *t*, or suitably attached thereto and formed of a separate strip of material, this being immaterial to my invention.
- 13 One or more doors *d* are provided in the wall portions *t'* of the tent, which form closures for substantially elongated openings *o*, and said doors may be arranged to be held in closed position by suitable devices.
- 14 One or more windows W, W, etc., are also provided in the wall portions *t'* of the tent, which are preferably covered by strips of gauze material as at *g*, so as to prevent the entrance of insects to the interior of the tent.
- 15 The windows may be closed by suitable flaps, *f*, extensibly carried on the outer sloping sides of the wall portions *t'*, so as to partially or wholly close the windows as may be desired.
- 16 As hereinbefore stated, the frame for supporting the tent is composed of two composite members, namely, a central pole P and a circular ring R. Pole P is composed of a plurality of sections 1, 1, etc., with their abutting ends telescoped onto sleeves 2, 2, etc., which are substantially elongated and serve to cover the joints between the sections and to hold the pole rigidly in position.
- 17 The sleeves 2 may be permanently attached to one of the adjacent sections so that they will not be displaced from operative position. The bottom of the pole P may have a sleeve 3 attached thereto for forming a suitable rest on the surface of the ground.
- 18 The upper end of the pole carries a suitable sleeve 5 with a reduced extension 6, which is adapted to be inserted through an opening 7 in the top *t* of the tent, and a rope or cord 8 is preferably held within a circular seam 9 at the apex of the tent for reinforcing the portions *t* of the tent around the opening 7.
- 19 The circular ring R is composed of a plurality of sections 10, 10 etc. with their abutting end portions telescoped into short metallic sleeves 11, 11, etc., as shown in Figs. 8 and 12, and referring particularly to Fig. 12, it will be observed that the rods 10, 10, of the ring R are normally straight and are adapted to be made of spring steel or similar material, which may be bent inwardly on the normal curve of the tent, as shown in broken lines in Fig. 12, when the ring R is assembled, and which will have sufficient resiliency to restore the rods 10 to their normal straight lines, as indicated in full lines in Fig. 12, when the ring is dis-assembled.
- 20 When the members 10, 10, etc., and 11, 11, etc., are assembled together for completing the ring R a rigid structure of circular form is provided, and the adjacent ends of the members 10, 10, will be held in abutting positions by means of the resiliency in the members 10, 10, etc.
- 21 The ring R is positioned in and supported on the interior of the tent at the hip of the joint between the top portion *t* and the wall portion *t'*. Said ring may be supported, especially in the form of tent shown in Figs. 1 and 2, by means of a plurality of devices. 80 As shown in Fig. 3 this structure includes a plurality of flaps 13 made of the material of which the portions *t* and *t'* are made, and stitched to the tent wall at their edges 14, while their outer portions 15 have strips 16 85 of material stitched thereto and providing loops to which may be attached hooks *h* adapted to be adjustably connected to chains C composed of a plurality of links, and the uppermost link of each of said chains is attached to a strip of material 17 attached to the wall of the tent, which may be reinforced by another strip of material 18.
- 22 Thus, one after the other, when the tent has been raised to its approximate height by 95 means of a pole P, and the ring R has been assembled, the hooks H are adjustably connected to the chains C for supporting the ring within the flaps 13 and between said flaps and the tent wall. Thus, as the ring is finally secured in position at its plurality of supporting points, the ring will hold the lower edge of the top *t* concentrically with respect to the pole P.
- 23 Now, the lower edge of the skirt or wall portion *t'* is preferably provided with an open seam 19 in which a rope or cord 20 is held, and at a plurality of points around this lower edge, preferably at the seams between the several strips forming the wall, 100 rings 21 having loops 22 and 23 formed thereon and disposed at right angles to each other are threaded onto the ropes or cords 20, and the outer loops 23 extend outwardly 105 from the tent wall and overlie the ground 110 so as to receive stakes S which are adapted to be driven into the ground for firmly holding the lower edge of the tent in position.
- 24 It is preferable that the diameter of the tent at the bottom should be substantially 115 greater than the diameter at the hip on the junction between the top and bottom as indicated in line 8—8 in Fig. 2.
- 25 As shown in Figs. 9 and 10, the tent structure is adapted to be braced against the 120 action of the elements to a greater or lesser degree by means of the structure shown in the drawings which constitute ample guys of adjustable character for this purpose. 125 These guys G, G, etc., are formed of single 130

pieces of rope or cords 24, and one end of each of said ropes has a snap hook 25 attached thereto by means of a metal sleeve 26, through which the rope is extended upwardly and downwardly, as shown, for providing a loop 27 for the reception of the hook 25, the end of the rope being knotted at 28 adjacent the sleeve 26 for preventing the detachment of the hook therefrom.

10 The opposite end of each of said guys is provided with a metallic sleeve 29 through which the rope 24 is extended, and the end of the rope is knotted at 30 for holding the member 29 in position thereon. This member 29 is of usual character and has an elongated portion 31 of arcuate cross section, with an opening 32 therein through which the central portion of the rope is extended, so that a loop 32' is provided above the surface of the ground which is connected with a loop 33 of a link 22 similar to that shown in Fig. 6, while the right angularly disposed loop 23 of said link receives a stake S driven at an angle into the ground. Thus, when the guy G is attached to a link 33 at the hip of the tent, as shown in Fig. 9, and to the ground by means of stake S, the member 29 may be pulled upwardly so that the rope 24 will move through the eye 32 thereof for tightening the guy G, and this structure will serve to brace the tent under normal conditions.

15 In Fig. 10, however, I have shown a slightly different arrangement of the guys G for bracing the tent under extreme conditions, where greater rigidity is desirable. This method incorporates the same structure shown in Fig. 9, with the exception that all of the guys G are provided with pins 34 which have eyes 35 through which the central portion of the ropes 24 are extended, and said ropes are knotted at 36 at the point of attachment to the pins 34, so as to hold said pins in stated positions.

20 Under extreme conditions the rope 24 may be slacked to a sufficient extent so that a tube or pipe 36' may be positioned between the ground and the guy, as shown in Fig.

10, the pin 34 being extended into the upper end of the tube 36', and the lower end of said tube being braced against the ground at or near the base of the tent, and disposed at an acute angle from the ground, so that any undue strains due to winds or some other elements will be directed against the ground rather than against the tent. Thus, the members 36' serve as struts in a truss which deflect the strains.

25 When the tent is assembled for use, the stakes S attached to the guys G are spaced substantially from the base of the tent so as to permit the interposition of the members 36' when occasion requires, without changing the stakes S.

30 As shown in Figs. 7 and 8, my type of tent structure adapts itself readily to the use of only the top portion *t* without the wall portion *t'*, and this feature is desirable especially for seaside resorts and for providing sun shades for the beaches and other 35 places where the full camping equipment is not necessary.

35 In the use of this type of device one of the sections of the central pole P may be omitted so as to bring the top *t* of the tent 40 down closer to the ground, and the guys G may be employed in connection with this tent in either of the forms shown in Figs. 9 and 10, as may be necessary and depending upon conditions.

45 What I claim is:

The tent structure including a tent, means for supporting the same on the ground in extended position, and a circular member carried on the wall of said tent for holding the same extended concentrically with respect to said supporting member, said supporting member and said circular member being composed of a plurality of telescoping sections, flexible members attached to the 50 interior of said tent forming loops for holding said circular member in position, and means for adjustably attaching said flexible members for stretching the tent to a desired extent.

SAM R. SMITH.
